UNITED STATES PATENT OFFICE.

FREDERICK A. PRESTON, OF HIGHLAND PARK, ILLINOIS, ASSIGNOR TO MAINTENANCE EQUIPMENT COMPANY, OF CHICAGO, ILLINOIS, A CORPORATION OF ILLINOIS.

SWITCH-POINT PROTECTOR.

Application filed December 24, 1925. Serial No. 77,499.

My invention relates to railway switch edge with a flange 15 which in its operative position on a rail fits against the inner face 16 of the head of the rail so as to be engaged by the flange of a railway wheel and thereby force the railway wheel laterally with respect to the fixed rail. The body portion of the plate is somewhat thicker than the flange 15 and is provided near its upper edge with a shoulder 17 which fits against the lower surface 18 of the head of the rail. The lower edge of the plate is provided with a flange 22 formed at an angle corresponding to the inclination of the upper surface of the base flange 21 and normally rests upon said surface when it is applied to the rail. The portion of the plate 14 intermediate the shoulder 17 and flange 22 is curved outwardly with respect to the vertical flange of the rail base. The inclination of the flange 22 and the spaced relation of the shoulder 17 and the bottom surface of the flange 22 is preferably such that the plate when in its applied position has a wedging fit between the lower surface of the head of the rail and the top surface of the base flange 21. The lower portion of the plate is, preferably, though not necessarily, spaced a slight distance from the central web of the rail and provided with one or more spaced openings 23, each of which is adapted to receive one end of a clamping device 24.

10 A more specific object of the invention is to provide a switch point protector which is so constructed that it may be clamped to the base portion of a railroad rail. In this connection I aim to provide clamping means for attaching the protector to the rail base which may be easily and conveniently applied and which, if desired, may be so arranged as to abut against a stationary part of the road bed so as to resist creeping movement of the rail.

The invention has for further objects such other new and improved combinations, arrangements and construction of parts as will be hereinafter described and claimed for carrying out the above stated objects and such other objects as will appear from the following description.

In the drawing:

Fig. 1 is a plan view of a railroad rail and the end portion of the switch rail showing a switch point protector constructed in accordance with my invention applied to the running rail and showing the clamping means arranged in position to bear against a cross tie.

Fig. 2 is a view in perspective of the construction and arrangement of parts shown in Fig. 1.

Fig. 3 is a sectional view taken on line 3-3 of Fig. 1.

Fig. 4 is a view similar to Fig. 3 showing another embodiment of my invention, and

Fig. 5 is a view in perspective of the switch point protector removed from the rail.

Referring first to Figs. 1, 2 and 3 of the drawing, 10 designates a fixed railroad rail, 11 a switch rail, the tapered end 12 of which is movable into and out of engagement with one side face of the fixed rail, and 13 is one of the cross ties on which the said rails are supported. The switch protector shown in the above figures consists preferably of an angular plate 14 formed along its upper

In Figs. 1 to 3, inclusive, I have shown the plate 14 clamped to the rail by means of two clamps 24-24, but it will be obvious that one of said clamps may be omitted if the location of said plate with relation to a cross tie should be such as to make said omission necessary or desirable.

The clamps 24-24 may be of any suitable or preferred construction adapted to clamp the flange 22 of the plate to the upper inclined surface of the base flange 21 of the rail. In the drawing, I have shown each clamp as consisting of a bar 25 of resilient metal formed at one end with a hook shaped jaw 26 which extends into one of the openings 23 of the plate and bears against the upper surface of the flange 22 at a point near the web of the rail. The other end of the bar is provided with a shoulder 27 adapted to snap over the outer edge of the base flange 28 of the rail when the clamp is driven to its applied position. The distance between the jaw 26 and the upper surface of

the bar 25 is normally less than the combined thickness of the base flange 21 of the rail and the flange 22 of the protector plate, whereby the jaw and bar are spread apart 5 when the clamp is driven into gripping engagement with the upper surface of the flange 22 of the plate and the bottom surface of the rail base.

In operation the plate 14 is positioned 10 against one side face of the fixed rail a short distance in advance of the switch point 12 and is clamped in said position by means of one or more clamps 24. After the plate is positioned on the rail, each clamp is applied 15 thereto by hooking the jaw end thereof over the flange 22 of the plate and then driving the clamp in the direction of its length transversely of the rail until the shoulder 27 snaps over the opposite edge of the rail base. 20 When the clamp is driven home, the end of the jaw 26 extends into the opening 23 and bears against the flange 22 at a point between the side face 29 of the head of the rail and the vertical web 20 of the rail so that 25 the downward pressure of the clamp holds the flat surface 31 of the flange 15 firmly against the side face of the rail head. The side walls of the openings 23 provide abutments for opposite sides of the clamp so as 30 to prevent relative movement of the plate and clamp longitudinally of the rail. The clamp 24 is preferably applied to the rail so that the body portion 25 of the clamp will abut against one of the vertical faces of a 35 cross tie 13 so as to resist any longitudinal creeping movement of the rail.

In Figs. 4 and 5 I have shown a modified embodiment of my invention, in which the protector plate 14^a is formed along its lower 40 edge with a shoulder 19 adapted to bear against the vertical web of the rail base. In this embodiment the upper surface of the flange 22^a is formed with a centrally disposed groove 32 instead of the openings 23 shown in the preceding figures of the drawing. The groove 32 receives the jaw 26^a of the clamp 24^a so as to prevent relative movement of the plate and clamp. The jaw 26^a of the clamp 24^a is somewhat shorter than 45 the jaw 26 of clamp 24. In other respects the plate 14^a and clamp 24^a may be the same as the corresponding members shown in Figs. 1 to 3 inclusive.

While I have shown and described my invention in connection with two specific embodiments, it will be obvious that various modifications in structure might be made without departure from the spirit of my invention. I, therefore, wish it understood 55 that I contemplate all such changes in structure as come within the scope of the appended claims.

I claim:

1. A switch point protector comprising a 59 guard member adapted to engage one side

face of a railroad rail, and clamping means provided with a jaw portion for embracing one flange of the base of the rail and a portion of said guard to hold the guard in position on the rail. 70

2. A switch point protector comprising a guard member adapted to engage one side face of a railroad rail, and clamping means comprising a rail base embracing member formed with a portion for engaging the bottom surface of the rail base and with a jaw portion adapted to be forced into wedging engagement with a portion of said guard to clamp the guard on the rail. 75

3. A switch point protector comprising a guard member adapted to engage one side face of a railroad rail, and clamping means comprising a rail base embracing member formed with a portion for engaging the bottom surface of the rail base and with a resilient jaw portion adapted to be forced into wedging engagement with a portion of said guard to clamp the guard on the rail. 80

4. The combination with a fixed railroad rail and a movable rail having a tapered end 85 adapted to be moved into and out of engagement with one side face of said fixed rail, of means for protecting the tapered end of said movable rail comprising a guard formed with a portion for engaging the flange of a railway wheel to shift the same laterally of the rail and provided with a portion adapted to be wedged into the space between the bottom surface of the head of the rail and the upper surface of the rail base, and spring means 90 for securing said guard to said fixed rail. 95

5. The combination with a fixed railroad rail and a movable rail having a tapered end adapted to be moved into and out of engagement with one side face of said fixed rail, of means for protecting the tapered end of said movable rail comprising a guard formed with a portion for engaging the flange of a railway wheel to shift the same laterally of the rail and provided with a flange corresponding in angularity to one base flange of the rail, and means provided with a jaw movable transversely of the rail into gripping engagement with the flange of said guard and said rail base for clamping the flange of said guard to said base flange. 100 105 110 115

6. The combination with a fixed rail and a movable rail having a tapered end adapted to be moved into and out of engagement with one side face of said fixed rail, of means 120 for protecting the tapered end of said movable rail comprising a guard formed with a portion for engaging the flange of a railway wheel to shift the same laterally of the rail and provided with a flange corresponding in angularity to one base flange of the rail and means movable transversely of the rail into wedging engagement with the flange of said guard and said rail base and into gripping engagement with the opposite side 125 130

of said rail to clamp the said guard upon said fixed rail.

7. In a switch point protector, the combination of a guard member formed with a wheel engaging portion which normally bears against one side face of the rail head and an angularly disposed flange which normally rests upon the upper surface of the rail base, and means having a wedging engagement with said guard and the adjacent flange of the rail base for clamping said guard to the rail base with capacity for adjustment of the guard longitudinally of the rail.

8. In a switch point protector, the combination of a guard member formed along its upper edge with a wheel engaging portion and with a shoulder adapted to bear against the under face of the head of a railroad rail and provided along its lower edge with a flange which normally rests upon the upper surface of one base flange of the rail, and means for securing said guard to the rail comprising a clamp engaging the flange of said guard and the bottom surface of the said rail base; said guard being provided with an abutment normally engaged by said clamp to prevent relative movement of said clamp and guard longitudinally of the rail.

9. In a switch point protector, the combination of a guard member formed along its upper edge with a wheel engaging portion and with a shoulder adapted to bear against the under face of the head of a railroad rail, and provided along its lower edge with a flange which normally rests upon the upper surface of one base flange of the rail, a portion for engaging the central web of the rail, and formed with a recess; and means for securing said guard to the rail comprising a clamp formed with a portion which extends into said recess and having a portion which extends under the rail base and engages the bottom surface thereof.

10. In a switch point protector, the combination of a guard member formed along its upper edge with a wheel engaging portion and with a shoulder adapted to bear against the under face of the head of a railroad rail and provided along its lower edge with a flange which normally rests upon the upper surface of one base flange of the rail, a portion for engaging the central web of the rail, and formed with an opening through the body, and means for securing the guard to the rail comprising a clamp provided with a jaw adapted to extend into said opening and engage said guard near the web of the rail, and provided with a portion adapted to engage the bottom face of the rail base.

11. The combination with a fixed rail-

road rail and a switch rail adapted to be moved into and out of engagement with said fixed rail, means for protecting the movable end of said switch rail comprising a guard formed with a portion for engaging the flange of a railway wheel to shift the same laterally of the fixed rail and provided with a flange which normally rests upon the top surface of the rail base, and means for clamping said guard to the fixed rail comprising a bar extending under the rail base and formed at one end with a jaw adapted to be forced into clamping engagement with one base flange of the fixed rail and with the flange of said guard and provided at the other end with means for engaging the other base flange of said rail.

12. The combination with a fixed railroad rail and a switch rail movable into and out of engagement with the fixed rail, of means for protecting the movable end of said switch rail comprising a guard formed with a portion for engaging the flange of a railway wheel to shift the same laterally of the fixed rail and means for securing said guard to said fixed rail comprising a clamp engaging said guard and extending under the bottom of the rail base in a position to engage a stationary part of the road bed to resist creeping movement of the rail.

13. The combination with a fixed railroad rail and a movable switch rail, one end of which is moved into and out of engagement with the fixed rail, of means for protecting the movable end of said switch rail comprising a guard arranged on one side of the fixed rail in advance of the switch rail, and means for securing said guard to said fixed rail comprising clamping members engaging the guard adjacent opposite ends thereof and engaging the bottom surface of the rail base.

14. The combination with a fixed railroad rail and a movable rail having a tapered end adapted to be moved into and out of engagement with one side face of said fixed rail, of means for protecting the movable end of said switch rail comprising a guard arranged on one side of the fixed rail in advance of the switch rail and provided with a flange adapted to rest upon the upper surface of one base flange of said fixed rail and provided with a recess formed in the upper surface thereof, and means for securing said guard to said fixed rail comprising a clamp formed at one end with a portion adapted to fit in said recess and with a portion which engages the bottom surface of the said rail base, the arrangement of said guard and clamp being such that the clamp is moved to its gripping position by movement transversely of the rail.

FREDERICK A. PRESTON.
